UNITED STATES PATENT OFFICE.

OLIVER D. WALLET, OF PITTSBURGH, PENNSYLVANIA.

CONCRETE-PILE FORMER.

1,101,364.

Specification of Letters Patent. Patented June 23, 1914.

Application filed July 3, 1913. Serial No. 777,262.

To all whom it may concern:

Be it known that I, OLIVER D. WALLET, a subject of the King of Great Britain, residing at Pittsburgh, in the county of Allegheny and State of Pennsylvania, have invented certain new and useful Improvements in Concrete-Pile Formers, of which the following is a specification.

This invention relates to improvements in 10 the art of constructing concrete piles and more particularly to apparatus adapted to enable and facilitate the construction thereof.

The object in view is the provision of 15 means for providing a pocket or opening for receiving the material to form the cast comprising the pile, means being so designed as to enable application of the material comprising the concrete pile directly 20 to the earth or other foundation beneath the pocket forming apparatus, and also to enable ready removal of the pocket forming apparatus after the concrete pile has hardened.

25 The invention also comprises certain other constructions, combinations, and arrangements of parts as will be hereinafter more fully described and claimed.

In the accompanying drawings: Figure 1. 30 is a longitudinal vertical central section taken through an apparatus embodying the features of the present invention, the penetrating point being indicated as closed. Fig. 2 is a similar view of the same with the 35 penetrating point open and the parts positioned for receiving the concrete mass. Fig. 3 is a transverse section taken on the plane indicated by the line 3—3 of Fig. 1, looking downwardly. Fig. 4 is a detail plan view of 40 the penetrating point.

The apparatus of this invention may be used as has heretofore been proposed in this art, namely, by filling the hole made by the former, during the process of withdrawal 45 of said device. An especial advantage of the invention resides in the fact that a filling tube or equivalent means co-operates with the members of a sectional point to positively maintain the latter in open positions 50 during the process of filling in the concrete which forms the pile, there being no likeli-

hood under these conditions that the members of said point will be closed by the pressure of soft earth thereagainst, when the apparatus is used in very soft ground.

55 Referring to the drawings by numerals, 1 indicates a tube having an expansible point 2 at its lower end and at its upper end being engaged by a block 3 preferably of metal. A wooden block or other appropriate cushion 4 rests upon or in the recess formed in the upper end of the block 3 and is adapted to be struck by the hammer employed for driving the tube 1. A nested inner tube 5 is arranged within the tube 1, 60 and, during the descent of the tubes, the two tubes are connected by a cross pin 6.

65 The point 2 may be formed in various ways but preferably consists of a series of tapered plates 2' hinged as at 2'' to the lower end of the tube 1, each of the hinges 2'' being comparatively loose for allowing freedom of movement of the several plates 2'. Each plate 2' is preferably provided along one edge with a flange 7 which causes 70 the several plates 2' to be crowded toward each other by the pressure of the earth against the several flanges during penetration. Each plate 2' is provided with an internal ridge 2'' disposed to serve as a cam. 75 Each plate 2' is pivotally engaged by a chain 8 which extends upwardly to a point between the inner and outer tubes, that is, between tubes 5 and 1, and the upper end of each chain 8 is engaged by a spring 9 which 80 extends upwardly and is connected at its upper end portion to the outer surface of the inner tube 5. The springs 9 are maintained under sufficient tension during descent of the tube 1 to insure the maintenance of the plates 85 2' in their relatively closed position and thus insuring the constant presence of an appropriate penetrating point while the tube 1 is being driven. Cables 10, 10 are fixed to the tube 5 adjacent its upper end portion and 90 extend downwardly outside of the pipe 5 and through the sides of the tube 1, each of said sides being preferably provided with a roller 11 or other appropriate antifriction means past which the cable 10 extends. The 95 outer or free ends of the cables 10 are provided with rings or other attaching means 100

which are adapted to be engaged by the hooks of appropriate tackle, as for instance, tackle of differential pulleys, for pulling said cables longitudinally. After the pipe 1 has 5 been driven to the desired elevation, the pin or rod 6 is removed, the cables 10 are drawn upwardly a distance sufficient for effecting relative movement of the tubes 1 and 5, and thereby opening the point and causing the 10 parts to assume the position indicated in Fig. 2. Obviously the inner tube 5 will descend to the extent permitted by the surrounding earth. The block 3 is removed and an appropriate funnel 12 is introduced in 15 the upper end of the tube 5. The concrete mix is discharged through the funnel 12 down into the pipe 5 and is deposited on the earth or other base at the lower open end of pipe 5; the supply of concrete being continued until the pile is completed for the 20 length of the pipe 5 or for any other appropriate less length desired. After the concrete has taken its initial set but before it is sufficiently hardened to interfere with the 25 withdrawal of the pipes 1 and 5, the lifting devices engaging the cables 10 are caused to continue to lift until the said pipes are withdrawn from about the newly formed pile which is allowed to remain until it 30 thoroughly hardens and thereupon any material may be packed about it or, if preferred, the space left by the removal of the tubes 1 and 5 may be filled with fresh concrete. It is to be observed particularly that 35 when the parts are in the position indicated in Fig. 2, the pipe 5 has free access to the ground and is in no sense interfered with by the parts of the cap 2.

Having thus described my invention, 40 what I claim as new is:

1. In a concrete pile forming apparatus, a tube, a penetrating point normally closing the lower end of said tube and comprising sections expansible into open positions, 45 an inner tube arranged within the first mentioned tube and movable relative thereto, and means for causing relative movement of said tubes to project the inner tube into engagement with said penetrating point and 50 thereby spread the sections of the latter to open the same.

2. In a concrete pile forming apparatus, a tube, a sectional penetrating point for said tube, an inner tube arranged within the 55 first-mentioned tube, the two tubes being adapted to have relative movement with respect to each other for shifting the sections of the point and opening the same, and a cable engaging the inner tube and extending 60 downwardly therefrom through the outer tube and adapted to have its outer end engaged and subjected to draft for effecting the relative movements of the tubes.

3. In a concrete pile forming apparatus, nested tubes, detachable means for sustaining the tubes in their relative positions, a penetrating point permanently connected with the outer tube, said penetrating point being formed of movable plates, and means engaging the inner and outer tubes and 65 shiftable relative thereto for effecting relative longitudinal movements of the tubes and simultaneously opening the parts of the penetrating point.

4. In a concrete pile forming apparatus, 75 the combination of nested tubes and a penetrating point for the outer tube comprised of plates hinged to the outer tube and converging to form a point, and means engaging the inner and outer tubes for effecting 80 relative movements thereof for causing the inner tube to strike the plates and hinge the same outwardly for opening the point.

5. In a concrete pile forming apparatus, 85 the combination of nested tubes, an openable point for the outer tube, and cables connected with the inner tube and extending longitudinally thereof and engaging the outer tube, said cables being adapted to be moved longitudinally for effecting relative 90 longitudinal movement of the tubes, the inner tube being proportioned for striking and opening the penetrating point when the relative movement of the tube is effected by movement of the cables. 95

6. In a concrete pile forming apparatus, the combination of nested tubes, a series of plates hinged to the outer tube, and springs engaging the inner tube and connected with the plates and tensioned for maintaining 100 the plates normally closed for retaining the form of a penetrating point, the two tubes being adapted to be given a relative longitudinal movement with respect to each other for swinging the plates outwardly by contact of the inner tube therewith. 105

7. In a concrete pile forming apparatus, the combination of nested tubes, a series of plates at the lower ends of the outer tube, hinged connections for said plates connecting the same to the outer tube, said plates being tapered for forming a penetrating point when in contact with each other, chains engaging the several plates, and springs connected with the chains and engaging the inner tube and tensioned for retaining the plates in the penetrating point forming relation, the tubes being adapted to be shifted longitudinally with respect to each other for causing the plates to be struck by the inner tube and opened thereby. 115 120

8. In combination, a former tube adapted to penetrate the earth, a point connected permanently with the lower end of said tube comprising sections adapted to spread 125 into open condition, and means for causing

opening of said point and for holding its sections positively open during withdrawal of the tube from the earth.

9. In combination, a former tube adapted to penetrate the earth, an openable sectional point therefor carried by its lower end, a filling tube within the former tube, and means for causing relative movement of said tubes to open the point aforesaid

and to cause the filling tube to assume a position locking the point in its open condition. 10

In testimony whereof I affix my signature in presence of two witnesses.
